FISH BOWL

Wade H. Wolfe, 5211 Arbardee Lane,
Fair Oaks, Calif. 95628

Filed Dec. 11, 1968, Ser. No. 14,892

Term of patent 7 years

Int. Cl. D30—01

U.S. Cl. D30—9

FIG. 1 is a side elevational view of my new design for a fish bowl;

FIG. 2 is a front elevational view thereof;

FIG. 3 is a top plan view thereof;

FIG. 4 is a rear elevational view thereof.

I claim:

The ornamental design for a fish bowl, substantially as shown.
